UNITED STATES PATENT OFFICE.

JOHN M. FISHER, OF SALT LAKE CITY, UTAH.

STOVEPIPE FASTENER.

Application filed December 31, 1924. Serial No. 759,130.

To all whom it may concern:

Be it known that I, JOHN M. FISHER, a citizen of the United States, residing at Salt Lake City, in the county of Salt Lake and State of Utah, have invented new and useful Improvements in Stovepipe Fasteners, of which the following is a specification.

The object of this invention is to provide improved means for securing a stove pipe 19 in a flue opening.

A further object is to effect this result by the use of a retaining device adapted to engage the wall of the flue and the inner end of the pipe, a bracket engaging the wall 15 or the collar at the outer end of the flue opening, and tension means applied in a particular manner as hereinafter indicated.

With the foregoing and other objects in view, the invention consists in the novel construction and arrangement of elements described, illustrated and claimed, it being understood that modifications may be made within the scope of the claims without departing from the spirit of the invention.

25 In the accompanying drawings,—

Figure 1 shows a pipe and elbow in side elevation; one end of the pipe entering a flue opening, and the pipe and elbow being secured in the manner described below;

30 Figure 2 is a perspective view of the retaining devices;

Figure 3 is a perspective view of a reel for the tension element, or wire.

A portion of the wall of a flue is shown 35 in vertical section, and is designated 10, being provided with a flue opening 11, through which the pipe section 12 enters the flue or communicates therewith. Elbow 13 is connected with pipe section 12 and with 40 a pipe section 14, the latter being broken away as shown. A collar 15 surrounds element 12 and serves the usual purpose.

The retaining device 16 of Figure 2 includes a horizontal portion apertured at 17, 45 a portion 18 at a right angle with the horizontal portion, and adapted to engage the inner end of pipe section 12,—and further includes a bent over and downwardly extending element 19, also at a right angle with the horizontal portion and adapted to engage 50 the wall of the flue, on the inner side, adjacent to the flue opening.

A bracket 20, shown in detail in Figure 2, 55 may be termed an angle bracket, and has an aperture 21. This bracket may project

through the opening of the collar and engage the collar.

The tension device consists of a wire 23 which may be wound on a reel or spool 24 having a hook member 25 formed thereon 60 and constituting a part of one end flange of the spool. If the spool is dispensed with, the surplus wire will be coiled, or cut off.

The wire 23 engages apertured portions 21 and 17, in the manner shown in Figure 65 2, and all of the elements of that view are positioned in the flue opening and outside of pipe section 12. The wire extends through collar 15 and encircles elbow 13, being secured by twisting at 26. If the 70 spool 24 is retained, the hook 25 engages portion 27 of the wire, the spool being left in position for further use, so that wire is immediately available if that portion used as here described is discarded when the pipe 75 is temporarily removed for cleaning purposes.

What I claim is:

1. The combination with a flue wall having an opening therein, of a pipe section 80 entering said opening, an elbow connected with the pipe section, a retaining device engaging the inner end of the pipe section and engaging the inner surface of the flue adjacent to the opening for the pipe, an apertured 85 angle element alongside of the pipe and projecting outwardly through the flue opening, one arm of the angle element acting to prevent said element from being drawn into the flue, and a tension element connecting the retaining device with the angle element, passing through the opening, and secured to the elbow.

2. The combination with a flue wall having an opening therein, of a pipe section 95 entering said opening, an elbow connected with the pipe section, a collar on said pipe section, a retaining device engaging the inner end of the pipe section and engaging the inner surface of the flue, an apertured 100 angle element projecting outwardly through the flue opening, one arm of the angle element engaging the outer surface of the collar, and a tension element connecting the retaining device with the angle element, 105 passing through the opening and collar, and secured to the elbow.

In testimony whereof I affix my signature.

JOHN M. FISHER.
